UNITED STATES PATENT OFFICE.

ALLEN HACKETT, OF LA GRANGE, MAINE.

SAW-GUIDE.

SPECIFICATION forming part of Letters Patent No. 286,295, dated October 9, 1883.

Application filed June 21, 1883. (No model.)

To all whom it may concern:

Be it known that I, ALLEN HACKETT, of La Grange, in the county of Penobscot and State of Maine, have invented certain new and useful Improvements in Saw-Guides; and I do hereby declare that the following is a full, clear, and exact description of the invention, that will enable others skilled in the art to which it appertains to make and use the same, reference being had to the accompanying drawings, forming a part of this specification, in which—

Figure 1 shows a plan of my invention; Fig. 2, section through line *a b*, thumb-nut in elevation.

Same letters show like parts.

My invention consists of an improvement in circular saw-guides readily adjustable and easily taken out of the way when the saw is to be removed from the arbor. It will be understood by reference to the annexed drawings.

At *a* is shown a box or casing closed at the top but open at the bottom to allow the escape of dust, &c., which might otherwise clog my device. This casing is secured to the machine-frame by bolts passing through slots to allow adjustment as the saw wears. Within the casing are independent levers *b c*, extending past the periphery of the saw, and having cavities near their ends, as common, to receive the wooden pins or pegs which come in contact with it. These levers are pivoted at *d d*. At *e f*, in the top of the box *a*, are slots cut upon a curve struck from the pivots *d d*, respectively, as centers. Through these slots pass bolts *g h*, entering threaded holes in the levers *b c*, and provided with broad shoulders

i, and also, if desired, with washers *j*, thus giving a broad bearing-surface upon the top 40 of the casing sufficient to resist any tendency of the levers to shift their position. By means of these slots and bolts or thumb-nuts the levers may be securely fixed in the position desired, while if it becomes necessary to remove 45 the saw for any reason, the outer lever, *c*, can be readily thrown to one side by loosening its nut.

I do not claim the devices shown in the patent of H. C. Berry, wood-turning lathe, No. 50 63,836, April 16, 1867, consisting of upright jaws carrying friction-rolls, against which the object in process of turning rests as a support instead of being embraced, as in my invention. My device is for an entirely different purpose, 55 and is radically different both in construction and operation.

What I claim as my invention is—

In a saw-guide, the combination of the casing *a*, secured to the frame of the machine by 60 slots and bolts, allowing adjustment as the saw wears down, inclosing levers *b c*, one on each side of said saw, pivoted to said casing at *d d*, said casing being provided with curved slots *e f*, struck from said pivots, respectively, as 65 centers, with thumb-nuts or bolts *g h*, passing through said slots and into said levers, whereby said levers may be fixed in any required position.

In testimony that I claim the foregoing I 70 have hereunto set my hand this 19th day of June, 1883.

ALLEN HACKETT.
